DRYING WOUND PACKAGES

Graeme G. Whytlaw, Swarthmore, Pa., assignor
to American Viscose Corporation, Wilmington,
Del., a corporation of Delaware

No Drawing. Application October 3, 1944,
Serial No. 557,062

10 Claims. (Cl. 34—7)

1
This invention relates to a method of drying filamentary material in the form of wound packages, and it is applicable particularly to those packages which lack a rigid internal support, such as rayon "cakes" formed within spinning buckets whether or not provided with the conventional protective cover of knitted fabric.

It has heretofore been suggested to apply an air and liquid-tight covering, such as an elastic sleeve or tube of rubber, about the outer and end surfaces of the windings or packages and then drying so that the drying proceeds progressively from the inside windings to the outside windings. In this manner, all of the windings are free to shrink, and by the time the outermost windings undergo drying, the inner windings have already shrunk so they do not restrain shrinkage of the outer windings, as would be the case if no covering were present. The previous practice of wrapping a cake with a wrapper entirely impervious to moisture during the whole course of drying has been found undesirable in that the entrapped moisture builds up an outer zone of high humidity and high temperature within the cake, causing dehydration of the filamentary material in the outer windings adjacent the wrapper with subsequent dyeing effects. It is the object of this invention to provide a wrapper which greatly retards the flow of moisture outwardly from the cake, thereby preventing undue case-hardening, but at the same time allows sufficient moisture to pass through the wrapper to prevent excessive building up of temperature and humidity within any portion of the cake.

In accordance with the present invention it has been found that dried yarns having uniform dyeing, shrinkage and tactile characteristics can be obtained with considerably shortened drying time and with negligible degradation by providing the packages to be dried with a moisture-absorbent but imperforate cover or wrapper comprising a sheet of cellulosic material exhibiting shrinkage on drying approximately corresponding to that of the filamentary material. In the specifications and claims, the word "sheet" is intended to refer to structures that lack any definite interstitial openings extending clear through the thickness thereof, and accordingly it excludes any such foraminous article as ordinary cloth.

Examples of materials of which covers for application to viscose rayon cakes may be made are thin sheets of paper or regenerated cellulose, such as in the form of Cellophane. Paper-like artificial "felts" comprising a mixture of cellulosic fibers and thermoplastic binder fibers, such

2
as of vinyl resins, in which one or both types may be of paper-making or textile-making length, are useful. Papers of the high-wet strength type are valuable provided they are moderately moisture-absorbent. In the claims, the term "paper" is intended to include these thin, paper-like artificial felts.

10 The cover is preferably in the form of a sleeve or tube longer than the cake and has a diameter somewhat larger than the outer diameter of the cake in the condition of application. The cover may be applied wet or dry. In general, application in the dry condition is preferred, but regenerated cellulose sleeves which have never been dried, but which are stored in moist condition such as in a vessel of water, may be applied wet with great advantage.

15 The covers used shrink to substantially the same extent as the cakes during drying. Commercially available papers having the appropriate shrinkage characteristic may be made originally in the form of a tube, or a flat sheet of appropriate size and shape may be formed into a tube, the overlapped ends being joined by a suitable waterproof adhesive.

20 In the case of the thin artificial "felts" mentioned above comprising thermoplastic binder fibers, the shrinkage may be partially or completely accomplished by virtue of the shrinkage tendencies of the binder fibers under the action of the heat used in drying. For this purpose, stretched fibers of vinyl chloride-acetate copolymer having a shrinkage temperature slightly below the temperature of the drying medium may be selected for making the artificial felt.

25 Cellophane tubes may be made by a process involving stretching during the drying, so that when placed about the rayon cakes they are free to shrink during drying of the wrapped cake.

30 40 After the cakes have been wrapped, they may be subjected to a heated drying medium in conventional fashion. The drying medium may conveniently be air and its relative humidity may be controlled so that it is gradually reduced from a high value to a low value during the drying.

45 When using the wrappers of the present invention it has been found that the drying can be accomplished more rapidly, and that, when controlled humidity is used, the reduction in humidity can be more rapidly accomplished than is possible with the wrappers heretofore used without encountering non-uniformity of shrinkage, dyeing, and other characteristics which normally result from case-hardening.

50 55 By using a moisture-absorbent wrapper which

shrinks during drying, a small proportion of the moisture gradually passes through the wrapper and is slowly vaporized at its external surface. Such vaporization causes the wrapper to shrink into firm contact with the windings, so that the wrapper can adsorb liquid in the cake and maintain itself in a partially dried condition throughout the period required for the main drying to progress from the inside to the outer windings of the cake. Thus, partial dehydration of the outer windings occurs and prevents the development of an outer zone of high temperature-high humidity conditions while rapid and complete dehydration progresses from the inner windings to the outer partially dried windings. The drying is thus effected without encountering the "stewing" of the outer windings which would hydrolyze the cellulose thereof.

The use of cellulosic material in the wrapper is advantageous in that the equilibrium set up between the moisture present in the outer windings and the wrapper is such as to assure slow passage of the moisture through the wrapper to maintain it in a but partially dried condition at all times until completion of drying of the cake, so that the wrapper clings to the cake but allows surplus moisture to gradually pass therethrough. In addition, the wrapper being made of the same material as the cake of rayon does not remove any finishes, such as soaps, oils, waxes, or the like, from the outer windings by selective absorption, and furthermore is not deleteriously affected by such finishes, as is the case of rubber wrappers when a mineral oil lubricant is present on the cake.

It is to be understood that changes and variations may be made without departing from the spirit and scope of the invention as defined in the appended claims.

I claim:

1. A method of drying a wound filamentary package of annular shape comprising the steps of covering the outer and end surfaces of the package with an imperforate moisture-absorbent sheet of non-fibrous material produced from a solution of cellulose and subjecting all surfaces of the wrapped package to a heated drying medium.

2. A method of drying a wound filamentary package of an annular shape lacking a rigid internal support comprising the steps of covering the outer and end surfaces of the package with an imperforate moisture-absorbent sheet of non-fibrous material produced from a solution of cellulose and subjecting all surfaces of the wrapped package to a heated drying medium.

3. A method of drying a wound filamentary package of annular shape comprising the steps of covering the outer and end surfaces of the package with an imperforate moisture-absorbent sheet of non-fibrous material produced from a solution of cellulose exhibiting a shrinkage approximately corresponding to that of the filamentary material and subjecting all surfaces of the wrapped package to a heated drying medium.

4. A method of drying a wound filamentary package of annular shape comprising the steps of covering the outer and end surfaces of the package with an imperforate moisture-absorbent paper tube exhibiting a shrinkage approximately corresponding to that of the filamentary mate-

rial and subjecting all surfaces of the wrapped package to a heated drying medium.

5. A method of drying a wound filamentary package of annular shape comprising the steps of covering the outer and end surfaces of the package with an imperforate moisture-absorbent regenerated cellulose tube exhibiting a shrinkage approximately corresponding to that of the filamentary material and subjecting all surfaces of the wrapped package to a heated drying medium.

10 6. A method of drying a wound filamentary package of annular shape comprising the steps of covering the outer and end surfaces of the package with an imperforate moisture-absorbent Cellophane tube exhibiting a shrinkage approximately corresponding to that of the filamentary material and subjecting all surfaces of the wrapped package to a heated drying medium.

15 7. A method of drying an annular wound package of rayon comprising the steps of covering the outer and end surfaces of the package with an imperforate moisture-absorbent sheet of non-fibrous material produced from a solution of cellulose exhibiting a shrinkage approximately corresponding to that of the rayon, and subjecting all surfaces of the wrapped package to a heated drying medium.

20 8. A method of drying an annular wound package of rayon comprising the steps of covering the outer and end surfaces of the package with an imperforate moisture-absorbent paper tube exhibiting a shrinkage approximately corresponding to that of the rayon, and subjecting all surfaces of the wrapped package to a heated drying medium.

25 9. A method of drying an annular wound package of rayon comprising the steps of covering the outer and end surfaces of the package with an imperforate moisture-absorbent regenerated cellulose tube exhibiting a shrinkage approximately corresponding to that of the rayon, and subjecting all surfaces of the wrapped package to a heated drying medium.

30 10. A method of drying an annular wound package of rayon comprising the steps of covering the outer and end surfaces of the package with an imperforate moisture-absorbent Cellophane tube exhibiting a shrinkage approximately corresponding to that of the rayon, and subjecting all surfaces of the wrapped package to a heated drying medium.
